UNITED STATES PATENT OFFICE.

CARL J. MELLIN, OF RICHMOND, VIRGINIA.

PISTON-VALVE.

SPECIFICATION forming part of Letters Patent No. 431,818, dated July 8, 1890.

Application filed January 23, 1890. Serial No. 337,887. (No model.)

To all whom it may concern:

Be it known that I, CARL J. MELLIN, a citizen of Sweden, and a resident of Richmond, in the county of Henrico and State of Virginia, have invented new and useful Improvements 5 in Piston-Valves, of which the following is a specification.

My invention consists of a contrivance of double ports both for the live steam and exhaust in a piston-valve to facilitate quick action.

It also consists of pass-ports contrived to bring instant communication between both ends of the cylinder just as compression commences on one side and directly before the beginning of exhaust on the other side of the piston to use the steam that has performed its work on one side to fill the clearance and cushion on the other. Said pass-ports also 20 act as inlet or steam ports, and, together with the aforesaid double live-steam ports, make it a triple-port steam-valve, as hereinafter fully described, reference being made to the accompanying drawings, in which—

Figure 1 is a longitudinal sectional elevation through a piston, valve-cylinder, and engine ports, illustrating my invention of double steam and exhaust ports. The section is taken on line 3 3, Figs. 3 and 4. Fig. 2 is 25 a diagram of the surface of one section of the valve of Fig. 1 expanded in a plane. Fig. 3 is a plan of the steam end of the valve. Fig. 4 is a plan of the exhaust end. Fig. 5 is a transverse section of the valve on line 1 1, Fig. 1; and Fig. 6 is a section of the same on line 2 2, Fig. 1. Fig. 7 is a longitudinal section of the double-ported steam and exhaust valve, also provided with the over pass-ports for filling the clearance and giving the cushion 30 on one side by the steam that has done its work on the other side, said section being half on I K and half on K L, Figs. 8 and 9. Fig. 8 is a half-section on A B and a half-section on C D, Fig. 7; and Fig. 9 is a half-section on G H and a half-section on E F, Fig. 7. Fig. 10 is a longitudinal section of the valve, 45 showing the pass-ports arranged for triple steam-ports only.

There are two ports *a* and *b* to the steam-way of each end of the engine-cylinder, both extending around the valve-cylinder *d*, sur-

rounding the valve *e*, and also being in communication through passage *c* in the valve-cylinder.

The valve is a piston of two sections located 55 apart from each other along the rod, to which both sections are coupled a suitable distance to provide requisite space for the exhaust-way between them. It receives the live steam on the outer ends, and the steam exhausts 60 between the adjacent ends of the two sections. Besides admitting steam directly from the ends into ports *a*, the valve has cored live-steam passages *f* in each section from the steam end communicating with the auxiliary steam-port *g* through the side of the valve and opening to cylinder-ports *b*, where the steam end of the valve opens to cylinder-ports *a*, and besides exhausting from ports *b*, at the inner or exhaust ends, the valve also has 70 cored exhaust-passages *h* from said ends communicating with the auxiliary exhaust-ports *i* through the side, which open to cylinder-ports *a*, where the exhaust ends of the valve open cylinder-ports *b* to the exhaust-passage *j*. 75 These live and exhaust steam passages *f* and *h* cross or overlap each other in the valve suitably to admit the live steam from the steam end of the valve to the steam-ports *b* through valve-port *g*, past the exhaust-port *i* 80 of the valve, and to allow the exhaust-steam to escape from port *a* through valve-port *i* past the steam-ports *g*, and out at the exhaust end of the exhaust-passage *j*. Both end sections are constructed alike and together distribute the steam for both ends of the engine-cylinder. In Figs. 1 to 6, inclusive, I have 85 represented three of these overlapping passages for live and exhaust steam, each in both sections of the valve, but may of course have 90 more or less, as desired. In Figs. 7 to 9, inclusive, I have represented four of each, besides the pass-ports described farther on.

It will be understood that the live steam may be received at the middle space and the 95 exhaust delivered from the outer ends of the valve as well, if desired, the operation being the same, the only difference being the proper change in the angular position of the eccentric, although in such case it will be better to 100 reverse the conditions of the ports *a* *b* and *g* as to their areas. I also propose to pro-

vide what I will call "over-pass" or simply "pass-ports," which may be single, but are also double as I have arranged them herein, and I class them as "outer" and "inner" pass-ports, as above stated, for filling the clearance and cushioning the piston on one side by the steam that has done its work on the other side. 5 *l* represents the inner and *m* the outer pass-ports. They all communicate with the central passage *k* in the valve and bring instant communication between both ends of the engine-cylinder just as compression commences on one side and directly before the beginning of exhaust on the other side. For 10 the purpose of these ports the valve is necessarily made with inside or exhaust lap, which it may have or not, as desired, so far as the rest of the invention is concerned, the said lap being equal to or slightly greater than the 15 length of the pass-ports in order that they shall always be out of communication with the exhaust-ports.

20 The inner pass-ports are located behind or inside of and in the same range with the inlet-ports *g* and have about the same shape, and the outer pass-ports have the same relation to the exhaust-ports *i*. It will be seen that the arrangement is such that at the moment when the inlet takes place neither the outer 25 nor inner pass-ports on the opening side are quite covered, so that for a short time they act as live-steam inlets also, and thus it is a triple-port inlet-valve as well, which with 30 double exhaust and double pass ports makes it feasible to reduce the diameter and stroke 35 considerably as compared with ordinary piston-valves. It is in most cases desirable to have the period of communication with both ends of the cylinder through these pass-ports 40 short as possible, but at the same time as effective as possible, which, it will be seen, is greatly facilitated by the arrangement of 45 double pass-ports, especially as the actual opening only amounts practically to half the length of said ports, for as they are opening on one side they are closing on the other—the exhaust side—where the exhaust opens the 50 moment the pass-port is closed.

55 It is to be noted that I have arranged the side ports and the pass-ports to extend entirely around the valve, so that the length of the opening lines is correspondingly increased and the size and length of stroke of the valve are reduced to the minimum, and with this I have also constructed the lateral openings of 60 the passage into the respective ports in the flaring shape merging in said circumferential ports, so as to render the whole of the circumferential lines of the ports available for effective work. I may utilize these pass-ports 65 for the triple steam-port only by arranging them, as I have represented in Fig. 10, so far out in the lap that no communication takes place between the ends of the cylinder.

70 In Figs. 7 and 10 the inner ends of the casting *x* of passage *k* are fitted with a ring *y* to confine them securely.

z in Figs. 1 and 3 represents eyelets for hooking into for lifting out the valve.

I claim as my invention—

1. The combination, with the valve-casing having double ports to each end of the cylinder, of the piston-valve having the middle space and inner and outer ports through the side between the middle space and each ends, 75 with longitudinal passages from the ends to the inner side ports, and other longitudinal passages from the middle space to the outer ports and intermediate to and crossing or overlapping the passages from the outer ends 80 to the inner side ports, and thus forming a double-ported steam and exhaust valve.

2. The combination, with the valve-casing having double ports to each end of the cylinder, of the piston-valve having the middle 85 space and inner and outer ports through the side and extending around the valve between said middle space and each end, with longitudinal passages from the ends to the inner side ports, and other longitudinal passages 90 from the middle space to the outer side ports and intermediate to and crossing or overlapping the passages from the outer ends to the inside ports, said longitudinal passages having the flaring lateral openings from between 95 the overlapping passages into the said circumferential ports, substantially as described.

3. The combination, with the valve-casing having double ports to each end of the cylinder, of the piston-valve having the middle 100 space and inner and outer side ports and the pass-ports through the side between said middle space and each end, with longitudinal 105 passages from the ends to the inner side ports, and other longitudinal passages from the middle space to the outer side ports, and the central longitudinal space connecting the pass-ports, the said passages of the inner and outer side ports being intermediate to and 110 crossing or overlapping each other, and the central passage having lateral openings into the pass-ports intermediate to the longitudinal 115 passages from the end of the valve to the inner side ports.

4. The combination, with the valve-casing 115 having double ports to each end of the cylinder, of the piston-valve having the middle space and inner and outer side ports and the pass-ports through the side and extending around the valve between said middle space 120 and each end, with longitudinal passages from the ends to the inner side ports, and other longitudinal 125 passages from the middle space to the outer side ports, and the central longitudinal space connecting the pass-ports, the said passages of the inner and outer side ports being intermediate to and crossing or overlapping each other, and the central passage having lateral openings into the pass-ports intermediate to the longitudinal 130 passages from the ends of the valves to the inner side ports, and all of said passages having the flaring lateral openings into the said circumferential ports, substantially as described.

5. The combination, with the valve-casing having double ports to each end of the cylinder, of the piston-valve having the middle space and inner and outer side ports and inner and outer pass-ports through the side between said middle space and each end with longitudinal passages from the ends to the inner side ports, and other longitudinal passages from the middle space to the outer side ports, and the central longitudinal space connecting the pass-ports, the said passages of the inner and outer side ports being intermediate to and crossing or overlapping each other, and the central passage having lateral openings to the outer pass-ports intermediate to the longitudinal passages from the ends of the valve to the inner side ports, and lateral openings to the inner pass-ports behind said passages from the ends to the inner side ports and between the passages from the middle space to the outer side ports.

6. The combination, with the valve-casing having double ports to each end of the cylinder, of the piston-valve having the middle space and inner and outer side ports, and the 25 pass-ports through the side between said middle space and each end, with longitudinal passages from the ends to the inner side ports, and other longitudinal passages from the middle space to the outer side ports, and the 30 central longitudinal space connecting the pass-ports, and thus being a triple steam and double exhaust valve, substantially as described.

In testimony that I claim the foregoing as 35 my invention I have signed my name, in presence of two witnesses, this 31st day of December, 1889.

CARL J. MELLIN.
